UNITED STATES PATENT OFFICE.

WINFIELD S. GROVE, OF MANILA, PHILIPPINE ISLANDS.

METHOD OF AND APPARATUS FOR DECORTICATING FIBROUS STOCK.

Application filed July 15, 1919. Serial No. 310,897.

To all whom it may concern:

Be it known that I, WINFIELD S. GROVE, a citizen of the United States, residing at Manila, Philippine Islands, have invented 5 certain new and useful Improvements in Methods of and Apparatus for Decorticating Fibrous Stock, of which the following is a full, clear, and exact description.

The object of the invention is to provide a 10 machine for removing the pulp and waste from fibrous vegetable plants and for extracting clean fibers from said plants free from pulp and other waste materials, the invention also relating to a method which 15 the machine is particularly adapted to perform.

The present machine is particularly adapted for obtaining fiber from the sheaths or strips of the trunk or stalk of the fibrous 20 plant known as abaca, commonly called manila hemp. The machine, however, can be readily adapted for the treating of sisal, maguey, pineapple or the like.

I have found it desirable to produce a 25 comparatively light, portable, power-driven fiber-extracting machine carrying its own motive power.

The present machine is designed to extract 30 clean fiber from the stalk with a minimum strain and without bruising, cutting or destroying the cellular construction of the fiber.

The machine is automatic, continuous running, requires but minimum attendance and 35 extracts fiber from the entire length of the sheath, strip or stalk, and automatically delivers the fiber from the machine, free from pulp or waste and comparatively free from water and acids which may have been present 40 at the commencement of the operation.

The present machine will hold the material to be cleaned during the operation of cleaning without bruising the fiber and reduce to a minimum the strain on the fiber 45 caused by the pull of the cleaning or decorticating members.

As showing certain specific embodiments 50 of the invention, reference is made to the drawings, forming part of this specification, and in which drawings:

Figure 1 shows in elevation a decorticating machine embodying my invention;

Figure 2 is a section taken on the line 1-1 of Figure 1;

Figure 3 is a plan view of the machine of 55 Figure 1, certain of the parts being broken away to show details of the machine;

Figure 4 is an enlarged elevational view of the upper part of the machine of Figure 1 with the parts in the position assumed at 60 the beginning of the decorticating operation;

Figure 5 shows in part sectional elevation 65 the decorticating members at the end of their rearward motion;

Figure 6 is a view similar to Figure 5, with one of the decorticating members moved to its extreme forward position and ready to perform the first part of the decorticating operation; 70

Figure 7 is an enlarged plan view of one 75 of the continuously moving stock-gripping devices;

Figure 8 is a view similar to Figure 7, taken on the line 9-9 of Figure 9, with the stock-gripping members in position to receive the stalk to be cleaned; and 80

Figure 9 is a section taken on the line 7-7 of Figure 7.

Referring to the drawings in detail, 1 85 designates a portable truck on which my improved machine may be mounted when in use in the field; 2 designates a motor mounted upon the truck and furnishing motive power to operate the machine; 3 90 designates the frame of the machine and 4 a drum mounted for rotation therein. The drum 4 is mounted on a shaft A carrying a gear 5 meshing with a pinion 6, this pinion being mounted on a shaft B carrying a pulley C, which pulley is driven by the motor 2 through a belt D whereby as the motor 2 is rotated motion will be imparted to the drum 4. 95

The drum 4 carries stock-gripping devices 7 (four in number), shown in detail in Figures 7, 8 and 9, and in position on the machine in Figures 1 and 2; each of these stock-gripping devices comprising a pair of stock-gripping members 8 and 9 mounted 100 in suitable brackets R and L at opposite sides of the periphery of the drum 4, by means of pivot pins 10 and 11. The stock-gripping members 8 and 9 comprise a pair of sectors provided with serrations or teeth 105 12 and 13, which are adapted to engage the stock to be cleaned and firmly grip the same, as will be described more in detail herein-

after, a pair of guide plates 68 and 69 to guide and help hold the stock in the serrations or teeth 12 and 13, and a pair of gear sectors 70 and 71. The gripping member 8 has an arm 17 integral therewith, which carries a roller 16 mounted on the stud 72. The pivot pin 10 carries a screw-eye 73, into which is hooked the spring 14, which is fastened to the drum by stud 74. The bracket 10 L carries the set screw 75 and lock-nut 76, which is set to limit or adjust the closed position of the serrations or teeth 12 and 13. The stock-gripping member 8 as the drum 4 rotates is adapted to be moved to a stock-releasing position by means of a stationary cam 15 adapted to be engaged by the roller 16. This movement of the member 8 is imparted to the stock-gripping member 9 by means of the gear sectors 70 and 71 against the tension of spring 14, and when the roller 16 leaves the cam 15, the stock being cleaned has already dropped upon the drum, and the spring 14 will then close the stock-gripping members 8 and 9 upon the stock. The plates 68 and 69 help to guide and hold the stock between the serrations or teeth 12 and 13, said serrations or teeth being cut eccentric to the centers of the gear sectors 70, 71, so that the pull on the stock will insure a perfect gripping or bending action upon the stock.

At the upper part of the frame 3 of the machine and directly above the drum 4 is provided a bed 18 on which are mounted carriages 45 and 46 adapted to be reciprocated longitudinally of the bed by means of an arm 20 pivoted at 21 and adapted to be rocked about its pivot through the medium of a cam 22. The upper end of the arm 20 is connected to the carriage 45 through the links 23. Mounted on the carriage 45 at the righthand end thereof, as viewed in Figure 1, are uprights 24 carrying a transversely-extending member 25 adapted to receive rods 26, the lefthand end of which rods, as viewed in Figures 3 and 4, for example, being secured to arms 27 of a stock-gripping member 27', the rods being mounted in the transversely-extending member 25 in such a manner as to permit the latter to be reciprocated without imparting motion to the rods themselves, except when the carriage 45 nears its extreme righthand position, as viewed in Figure 1.

The stock-gripping member 27' is mounted for partial rotation on a transversely-extending shaft 28, and has arms 29, to each of which are secured springs 30, the other ends of which springs are attached to the frame of the machine in any suitable manner.

The carriage 45 carries a knife or decorticating member 33 mounted rigid with levers 34 upon a transversely-extending rod 65 or shaft 35. The upper ends of these levers

have secured thereto one end of springs 36, the other ends of which are secured to the members 24, already referred to.

Mounted on the bed 18 in advance of the carriages 45 and 46 is a carriage 44 carrying a pusher member 31 adapted to engage an arm 32 connected with the stock-gripping member 27', for a purpose which will be more fully set out hereinafter.

The carriage 44 carries a decorticating member 37 having arms 38 and mounted upon a transversely-extending shaft 39. The upper ends of these arms carry rollers 40 adapted to engage the face cams 19, carrying the transversely-extending shaft 28 already referred to. Secured to the levers or arms 38 are springs 42, the other ends of which springs are secured to the frame 3 of the machine.

Carried by the carriage 45 and contiguous to the members 24 is a stop 43 provided for the purpose of limiting rearward movement of the stock into the machine when the machine is in operation.

The carriage 46 carries a pair of pivoted arms or gatherers 48, and an additional pair of pivoted arms or gatherers 47 are mounted on the bed 18 in advance of the gatherers 48, these gatherers being provided for the purpose of gathering the fibers of the stock after the same have been cleaned, so that when the fibers fall upon the periphery of the drum 4 the stock may readily be gripped by the stock-gripping members 8 and 9 carried thereby.

The carriages 45 and 46 are movable independently of each other, but at the first part of the forward movement of the carriage 45 they are moved simultaneously by reason of engagement of the transverse member 24 carried by the carriage 45 with the releasing members 41 mounted on the carriage 46, until a predetermined position has been reached, at which time pins 47', carried in the guideways in the bed 18, engage the cam surface of the release members 41. The release members 41 being pivoted on pins 49 carried by the carriage 46 when engaged by the pins 47' will be rocked about their pivots and out of engagement with the lower ends of the members 24. The carriage 45 may now continue to move forwardly, independently of the carriage 46. At this time, also, the pawls 50 carried by the carriage 46 will have been moved to a position to engage the pins 51 in the path of travel of said pawls, so that at this time, although the carriage 46 is no longer in engagement with the carriage 45, movement of the former to the rear, under action of the springs 52 and 53, is prevented.

In operation, the parts we will assume are first of all in the position shown in Figure 1, with the drum rotating constantly in a clockwise direction.

As the cam 22 moves relatively to the roller 54 on the arm 20, the latter is rocked to the left from the position shown in Figure 1, carrying with it initially both 5 carriages 45 and 46, the decorticating member 37, having no effect, however, at this time upon the stock-gripping member 27', the rods 26 riding freely in the transverse member 25, as already described.

10 The parts continue this movement to the left as viewed in Fig. 1 until the lower ends of the levers 34 engage fixed stops 34' secured rigidly to the frame 3 and until 15 pusher blocks 55 on the carriage 45 engage blocks 56 carried by the carriage 44, this carriage up to this time having remained stationary.

As the levers 34 contact with the fixed stops 34', the former will be swung about 20 their pivot 35 to carry the decorticating member 33 upwardly to the position shown in Figure 4, for example. The pins 47' in the bed 18 for the carriage 46 will in the meantime have engaged the cam face of the 25 release members 41 as shown in Fig. 6 at the rear end of the carriage to cause the release members to be depressed and moved out of engagement with the members 24, so as to disconnect the carriages 45 and 46 from 30 each other, permitting the carriage 45 to continue its forward movement, the carriage 46 now being locked in the position which it has now assumed by engagement of the pawls 50 with the pins 51 as shown 35 in dotted lines in Fig. 3. On the forward movement of the carriage 46 the offset E carried by each of the gatherers 48 will be brought into engagement with lugs F on the bed 18 and the gatherers will be swung about 40 their pivots as indicated in dotted lines in Fig. 3, carrying with them the gatherers 47.

As the carriage 45 continues its forward movement, the pushers 55 engage the blocks 56 carried by the carriage 44, and the latter 45 will be moved forwardly, carrying the decorticating member 37, the rollers 40 on the levers 38 riding up the face of the cams 19, to cause the decorticating member 37 to be raised to the position shown in Figure 4.

50 It is to be noticed at this time, also, that the pusher member 31 of the carriage 44 has engaged the arms 32 connected to the stock-gripping member 27' to cause the latter to be swung upwardly about its pivot so that stock 55 may be fed to the machine.

The parts are now in the position shown in Figure 4 and in such a position that the stock may be fed from the lefthand end of the machine longitudinally of the carriages, 60 passing beneath the stock-engaging portion of the stock-gripping members 27' and the decorticating members 37 and 33 until finally its forward end engages the stop 43, the stock resting upon the beds 59 and 60 of carriages 44 and 45, and base 58.

By this time the cam 22 has moved to such a position with respect to the roller 54 on the arm 20 as to cause the arm to move to the right about its pivot carrying with it the carriage 45. The carriage 44 under the 70 action of its spring 61 follows the rearward movement of the carriage 45, moving rearwardly until it engages the end 62 of the bed 18. This movement of the carriage 44 carries the pusher member 31 out of engagement with the arms 32 of the stock-gripping member 27', so that the same may be actuated by its spring 30 to a position to grip the stock. As the carriage 44 moves rearwardly the rollers 40 move down the face 75 of the cams 19, thus permitting the springs 42 to pull the decorticating member 37 downwardly into the position shown in Figure 1, for example.

As the carriage 45 moves rearwardly and as soon as the lower ends of the levers 34 move out of engagement with the stops 34', the decorticating member 33 will be moved downwardly about its pivot under the action 80 of the springs 36 into decorticating position.

The parts are now in position to perform the first decorticating step, the stock being held stationary by the stock-gripping member 27' as already described and the continued rearward movement of the decorticating member 33 under the action of the arm 20 will decorticate the righthand portion 85 of the stock as viewed in Figure 1, for example.

As the carriage 45 moves rearwardly, with the decorticating member 33 functioning as just described, the releasing lever 63, (see Figs. 3 and 4) carried by the carriage, engages cam surfaces 64 on the heads of the pins 51 already referred to, cause the latter to be moved outwardly against the action of the springs 65 and out of engagement with the pawl 50 to release the carriage 46. The latter, under the action of its springs 52 and 53, will now be moved rearwardly and at the same time the gatherers 47 and 48 will be moved under the action of their springs G and H to the full line position shown in Figure 3, to gather the stock into a comparatively compact mass, so as to be readily gripped by a set of the stock-gripping members — already described — carried by the drum 4 of the machine.

The righthand portion of the stock is now 110 decorticated, and the gatherers 47 and 48 have operated, due to the rearward movement of the carriage 46. This decorticated portion of the stock will fall upon the periphery of the drum and the operation of the machine is so timed that the stock will fall upon the drum as one of the sets of gripping members 8 and 9 are approaching a position to grip the same, holding of the stock in the gripping members being aided by the plates 68 and 69 carried thereby.

130

As the carriage 45 nears the limit of its rearward movement, the transversely-extending member 25 contacts with nuts carried at the righthand end of the rods 26 to cause the rods to be pulled to the right as viewed in Figure 4, for example, to open the stock-gripping member 27', so that when a set of stock-gripping members on the periphery of the drum grip the stock, the stock will be released from the stock-gripping member 27' and is free to be moved beneath the decorticating member 37, so that the remainder of the stock will be decorticated. It should here be noted that the decorticating member 37, when moved to operative position, overlaps the cleaned portion of the stock, to insure the entire stock being decorticated. As the drum rotates, carrying with it the decorticated stock, the remaining portion of which is now being decorticated, the rollers 16 of the stock-gripping members 8 and 9 will engage the cam 15 and be moved thereby to stock-releasing position to enable the stock to be discharged from the machine, assisted by the scraper 77 pressing against the periphery of the drum, to the take-off table 78, in a completely decorticated condition. It may here be mentioned that as many sets of stock-gripping members 8 and 9 may be provided on the periphery of the drum 4 as may be found necessary, it being obvious that it is essential to have a sufficient number of these gripping members to enable the stock to be always gripped and pulled beneath the decorticating member 37, until completely decorticated.

The parts are now in the position shown in Figure 1, for example, and as soon as the cam 22 has functioned to carry the arm 20 to its extreme lefthand position, the next supply of stock may be fed to the machine to be decorticated.

From the foregoing it will be seen that I have provided a machine for the purpose of decorticating fibrous stock, which is capable of continuous operation, thoroughly decorticating the stock and automatically discharges the decorticated stock from the machine. It will be obvious, also, that in the present machine the strain upon the stock being decorticated has been reduced to a minimum.

Obviously, if desired, the gripping members herein shown and illustrated could be replaced by carriers on a horizontally moving endless chain or belt so that the stock could be fed horizontally at all times and discharged from the machine in a horizontal manner, without departing from the spirit and scope of my invention. Other changes in the details of construction could obviously be made by one skilled in the art without departing from my invention.

I claim:

1. The method of removing the pulp and waste from fibrous vegetable plants in two

operations, consisting in first gripping one portion of the stock and holding the same stationary, removing the pulp and waste from the ungripped portion of the stock while the stock is so held, then gripping the portion of the stock from which the pulp and waste has been removed and moving the same and while the stock is in motion removing the pulp and waste from the remainder thereof. 75

2. In a machine for removing pulp and waste from fibrous vegetable plants in two operations, the combination of means for gripping a piece of stock to hold the same substantially stationary, means for removing the pulp and waste from a portion of the stock while the stock is so held, movable gripping means for gripping that portion of the stock from which the pulp and waste have been removed to set the stock in motion and means for removing the pulp and waste from the remainder of the stock while the stock is in motion. 80

3. In a machine for removing pulp and waste from fibrous vegetable plants, means for removing the pulp and waste from a portion of the stock while the stock is stationary and means actuated during movement of the first-mentioned means to operative position for holding the stock stationary during the removal of the pulp and waste. 85

4. In a machine of the class described, means for decorticating a portion of the stock while the stock is stationary, means for decorticating the remainder of the stock while the stock is in motion, said last-named decorticating means being controlled by the first-named decorticating means. 90

5. In a machine of the class described, means for decorticating a portion of the stock while the stock is stationary, means for decorticating the remainder of the stock while the stock is in motion, gripping means for the stock controlled by the first-named decorticating means and cooperating with the second-named decorticating means whereby the latter will be moved automatically to inoperative position as the first-named decorticating means is moved to operative position. 95

6. In a machine of the class described, a rotatable drum, stock-gripping means carried thereby, means for decorticating a portion of the stock while the stock is stationary, and means for decorticating the remainder of the stock while the stock is being held by said gripping means and the drum is rotating. 100

7. In a machine of the class described, a continuously rotating drum, stock-gripping means carried thereby, means for holding the stock stationary, means for decorticating a portion of the stock while being held by said last-named means, and means for de- 105

corticating the remainder of the stock while being gripped by the said stock-gripping means carried by the drum.

8. In a machine of the class described, a continuously rotating drum, stock-gripping means carried thereby, means for decorticating a portion of the stock while the stock is stationary, means for decorticating the remainder of the stock while gripped by said stock-gripping means, and means for automatically releasing said stock-gripping means and discharging the completely decorticated stock from the machine.

9. In a machine of the class described, the combination of a pivoted arm, a plurality of decorticating means controlled thereby, and means for actuating said arm to cause one of said decorticating means to function to decorticate a portion of the stock while the stock is stationary, and thereafter another of the decorticating means to decorticate the remainder of the stock while the stock is in motion.

10. In a machine of the class described, the combination of a pivoted arm, a continuously rotating drum, a cam for rocking said arm about its pivot and actuated by rotation of said drum, and decorticating means controlled by said arm, one of which functions to decorticate a portion of the stock while the stock is stationary, another of which functions to decorticate the remainder of the stock while the latter is in motion due to the rotation of said drum.

11. In a machine of the class described, the combination of a stock-gripping member, means for actuating the gripping member to operative position, a decorticating member, actuating means therefor control-

ling the stock-gripping member to move the same into position to release the stock as the decorticating member ceases to function.

12. In a machine of the class described, the combination of a stock-gripping member, means for actuating the same to operative position, a rotatable drum, a decorticating means, actuating means therefor controlling the first-named stock-gripping member to cause the same to be moved out of operative position as the decorticating member ceases to function, and stock-gripping means carried by the drum for receiving the decorticated portion of the stock when the first-named stock-gripping member is moved to stock-releasing position.

13. In a machine of the class described, the combination of means for decorticating one portion of the stock while the stock is held stationary, means for decorticating the remainder of the stock while the stock is in motion, and means for moving said last-named decorticating means into operative position during the first-mentioned decorticating operation and without moving the stock.

14. In a machine of the class described, the combination of means for decorticating a portion of the stock while stationary, means for decorticating the remainder of the stock while the stock is in motion, and means for automatically discharging the completely decorticated stock from the decorticating machine.

In testimony that I claim the foregoing, I have hereunto set my hand the 11th day of July, 1919.

WINFIELD S. GROVE.
